Primary Examiner — John A Voytek(74) *Attorney, Agent, or Firm* — Schwartz Law Firm, P.C.(57) **CLAIM**

I claim the ornamental design for a scent diffuser lid, as shown and described.

DESCRIPTION

FIG. 1 is a top perspective view of the scent diffuser lid; FIG. 2 is a further top perspective view thereof; FIG. 3 is a bottom perspective view thereof; FIG. 4 is a top view thereof; FIG. 5 is a bottom view thereof; FIG. 6 is a first side view thereof; FIG. 7 is a second side view thereof; FIG. 8 is a third side view thereof; and, FIG. 9 is a fourth side view thereof.
 Features of the scent diffuser lid shown in broken lines in the drawings form no part of the claimed design.
